UNITED STATES PATENT OFFICE.

JOHN QUINCY ADAMS AND SAMUEL HOUGH, OF ATCO, NEW JERSEY.

MOWER.

SPECIFICATION forming part of Letters Patent No. 703,513, dated July 1, 1902.

Application filed July 21, 1900. Serial No. 24,355. (No model.)

To all whom it may concern.

Be it known that we, JOHN QUINCY ADAMS and SAMUEL HOUGH, citizens of the United States, and residents of the village of Atco, county of Camden, and State of New Jersey, have invented certain new and useful Improvements in Mowers, of which the following is a clear, full, and sufficient specification, reference being had to the drawings annexed.

10 In our device horizontally-rotating knives are used as the cutting means and are rotated by suitable gearing from driving-wheels.

Figure 1 is a plan view of our invented device. Figs. 2 and 3 are detail views of the 15 ratchet mechanism. Fig. 4 is a detail view illustrating the action of the rotary knives on the stationary knife. Fig. 5 is a view of a modification, and Fig. 6 is a side elevation of the device of Fig. 1 with the rotating knives 2c except two removed.

The wheels 22, bearing the blades 333, &c., are set on the forward part of the main frame and rotate in a substantially horizontal plane. The axes of the wheels 22 are preferably located at such distance apart that the blades 25 33 of one wheel will not overlap the blades of the other as the wheels rotate, as shown. The driving mechanism for these wheels 22 keeps them in positive connection with each 30 other, and hence preserves the interval between these knives 33. We use for this mechanism the shaft 7, provided with the bevel-wheels 66, which engage with the bevel-wheels 55, which drive the wheels 22. It 35 will readily be seen that the rapidity of the movement of the knives 333 through the herbage to be cut is greatest where the knives project outward from the machine at right angles with the direction of the machine's 40 forward movement, where their movement is equal to their angular movement plus the forward movement of the machine, and is slowest where they point inward, where their movement is their angular movement less the forward movement of the machine. Accordingly 45 we give the knives during the slower portion of their movement a shearing movement by placing across the frame the stationary knife 9, which the knives 333 slide upon 50 with a shearing action. We drive the shaft 7 by a suitable gearing from the shaft 24, as by the sprocket-wheels 27 and 23 on the shafts

7 and 24, respectively, and the chain 22. The chain 22 connects the sprocket-wheels 23 and 27 above mentioned. The shaft 24 is driven 55 by the driving-wheels 2626, which are connected therewith through a suitable ratchet mechanism. This mechanism is constituted as follows: The shaft 24 is revolubly mounted in the frame, being held in place by the collars 2525. Upon this shaft are mounted the drive-wheels 2626, so that they can turn independently thereof except when prevented by the ratchet mechanism, in the hubs of which wheels are the sockets 3434, (see Figs. 60 2 and 3,) which contain the plungers 3232, pressed by springs 3333 toward the shaft 24 and engaging with a ratchet-wheel 30 thereon. The knife 9, which, as shown, is secured to arms or extensions of the main frame in 70 front of the axes of the wheels 22, may in many cases be omitted, since it is only required because the herbage might not be cut by the blades or knives where they move through it more slowly. 75

The operation of the device is as follows: As the machine moves forward the drive-wheels drive the wheels 22 through the intermediate gearing. The knives 3333 on wheels 22 cut the herbage by a sickle action, 80 which owing to the rapidity of their movement and the fact that only the end of the blade of the knife will usually do the cutting will be very effective. At the portion of the course of the knives where they slide upon 85 the fixed knife 9 the cutting will be in the nature of a shearing action, thus insuring a cutting where the blades of the knives move most slowly through the herbage. When the machine is moved backward, the drive-wheels 90 alone revolve, and when the machine turns the shaft 24 moves with the one of the drive-wheels turning the most rapidly if either of them is moving forward.

A modification is shown in Fig. 5, in which 95 a single wheel 43 is provided with knives 4242 and is connected through the bevel-wheels 46 and 50 and chain 44 and sprocket-wheels 43 and 45 with the shaft 52, which is rotated by one of the drive-wheels 5353. The object 100 of the large sweep of the knives 424242 and the decided difference in size of the bevel-wheels and the sprocket-wheels is to so speed up the knives that they will cut throughout

their course. The knives in this and in the first-described form of our device are so set that they slant toward the direction of the motion of the knife-carrying wheel, thus drawing the edge of the blade over the herbage to be cut.

Having now described our invention, what we claim, and desire to secure by Letters Patent, is—

1. The combination of a pair of drive-wheels, a horizontal shaft, ratchet mechanisms connecting said wheels to said shaft, disks revolving in a horizontal plane, knives secured to the upper side of the said disks and having their cutting edges inclined outwardly and in the direction of the disks' rotation, a driving mechanism between said disks and the said shaft, a straight cutter-bar located with its cutting edge substantially tangential to said disks, and extending transversely of the machine; substantially as described.

2. The combination of a pair of drive-wheels, a horizontal shaft, ratchet mechanisms connecting said wheels to said shaft, disks revolving in a horizontal plane, knives secured to the upper surface of said disks and

having a cutting edge inclined outwardly and in the direction of the disks' rotation, connecting mechanism between said disks, sprocket-wheels on said connecting mechanism, and on said shaft, a drive-chain connecting said sprocket-wheels, and a straight cutter-bar with its cutter edge substantially tangential to the disks and extending across the machine substantially as described.

3. The combination of a pair of drive-wheels, a horizontal shaft, ratchet mechanisms connecting said wheels to said shaft, disks revolving in horizontal planes knives secured to the upper side of said disks and a portion of said knives lying in a plane parallel with but below the plane of revolution of said disks, and a straight cutter-bar located with its cutting edge substantially tangential to said disks and extending transversely of the machine; substantially as described.

In witness whereof we have hereunto set our hands this 15th day of June, 1900.

JOHN QUINCY ADAMS.
SAMUEL HOUGH.
